UNITED STATES PATENT OFFICE.

LOTHAR VON DABROWSKI, OF CHICAGO, ILLINOIS, ASSIGNOR TO AMERICAN CAR AND FOUNDRY COMPANY, OF NEW YORK, N. Y., A CORPORATION OF NEW JERSEY.

REFRIGERATOR CAR.

Application filed February 7, 1923. Serial No. 617,625.

In the drawings:

Fig. 1 is a vertical transverse section of the car showing the method of securing the outer sheathing of the car to the car framing and the insulation material to the outer sheathing.

Fig. 2 is a fragmentary view in vertical longitudinal section showing a similar construction at the end of the car.

Fig. 3 is a horizontal section of one corner of the car showing the application of the insulation to the outside sheathing at the side and end of the car and showing the ice compartment bulkhead in position.

Fig. 4 is a similar section showing the continuation of the side wall construction of the car to the door opening; and

Fig. 5 is a vertical transverse section taken on line 5—5 of Fig. 3 looking in the direction indicated by the arrows and showing the method of assembling the outer sheathing with the exterior framing members of the car, and securing the insulation and inside sheathing to the outer sheathing of the car.

My invention relates to refrigerator cars and has for an object the provision of a construction in which the framing elements of the car function independently of the insulating walls of the car in taking up the stresses of service.

The principal object of this invention is to provide a single sheathed refrigerator car to secure maximum load carrying capacity with a minimum of dead weight.

Referring to the drawings—10 designates the center sills of the underframe of the car, 11 the side sills thereof, 12 the exterior upright side framing members of the car superstructure, and 13 the top plates thereof. The side framing members 12 are secured to the side sills 11 and top plates 13. Secured to the framing members are the side wall boards 14 held to such members by means of bolts 15 or other like fastening means. To these side wall boards is secured the insulation material comprising a number of layers of hair felt or other insulating fabric 16, held thereto by means of upright cleats 17 secured to the side wall boards by means of bolts 18. This insulation, it will be noted, is held to the side wall boards by means independent of the means securing the side wall boards to the car framing. To complete the insulating wall structure in-

side sheathing boards 19 are provided and these boards are secured to the insulation holding cleats 17 in any suitable manner.

The inside face of the outer wall boards 14 is rendered impervious to moisture preferably by means of a water proof compound or fabric applied in any suitable manner to the boards. In the same fashion the insulation side face of the inside sheathing boards 19 is treated to provide an absolutely water and air tight compartment 20 affording a dead air space to further enhance the insulation value of the side wall structure.

The end wall is similarly constructed. The car framing end members 21 are secured to the end sill 22 of the underframe and at their upper ends to the top end plates (not shown). To these framing end members 21 are secured the end wall sheathing boards 23 held to the framing by bolts 24, or the like, and to the end boards the insulating elements comprising the hair felt 16, cleats 17, and inside sheathing boards 19, are secured by the bolts 25.

As shown in the drawings the floor 9 and ceiling structure 8 of the car are also insulated in any approved manner, and respectively serve to seal the lower and upper ends of the dead air space 20 in the side wall insulation assembly.

The ice compartment 26 is separated from the provision chamber 27 by the insulated bulkhead 28 extending between the side walls of the car and secured thereto in any suitable manner.

It will be noted that there has been provided a refrigerator car construction employing but one course of boards to shield the interior of the car from the elements and to this single course of wall boards the insulating wall elements are secured, such insulating wall elements being supported independently of the car framing members and thus relieved of the stresses induced by the vibration set up in the car framing. The bolts securing the outer sheathing boards to the exterior car framing members do not extend to the car interior, nor do the bolts holding the insulation to the outer sheathing boards, thereby eliminating all metallic communication between the car interior and outside atmosphere and preventing the entrance of the warmer outer air to the car or the escape of the colder air of the car to the atmosphere. There is no direct metallic or

thermoconductive connection between the insulative lining 16 on the exterior wall 14 and its (external) framing 12, nor between this framing 12 and the inner wall 19,—notwithstanding that the inner wall 19 is carried by the outer wall 14 through the cleats 17 and bolts 18 whereby the insulation 16 is secured to the outer wall. The inner wall assembly formed by the insulation 16 and the inner boards 19 is made more effectively thermoinsulative by its air-chambering interspace 20.

What I claim is:

- 15 1. A refrigerator car construction comprising an exterior wall with its framing, and an inner wall carried by said exterior wall but spaced therefrom, and secured to said exterior wall without direct thermoconductive connection to said framing.
- 20 2. A refrigerator car construction comprising an exterior wall with external framing and internal insulation secured thereto independently of said framing and without direct thermoconductive connection thereto, and an inner wall carried by said exterior wall, but spaced from its internal insulation, and secured to said exterior wall without direct thermoconductive connection to said framing.
- 25 30 3. A refrigerator car construction comprising an exterior wall with external fram-

ing and internal insulation secured thereto independently of said framing and without direct thermoconductive connection thereto, and an inner wall spaced from the insulation of said external wall and carried from said external wall through the means securing its insulation as aforesaid.

4. A refrigerator car construction comprising an exterior wall with external framing and wall boards secured thereto, an insulative lining on said exterior wall, with cleats securing the same to said wall boards without direct thermoconductive connection to said framing, and an inner wall of boards carried by said cleats.

5. A refrigerator car construction comprising an exterior wall with external framing, and an insulative inner wall assembly carried by said exterior wall and secured thereto without direct thermoconductive connection to said framing.

6. A refrigerator car construction comprising an exterior wall with its framing, and an air chambered insulative inner wall assembly carried by said exterior wall and secured thereto independently of said framing and without direct thermoconductive connection thereto.

In witness whereof I have hereunto set my hand.

LOTHAR VON DABROWSKI.
